HERMAN L. DORFMAN AND MORRIS GROSSMAN, OF NEW YORK, N. Y., ASSIGNEES OF ONE-HALF TO MOLLIE GROSSMAN AND ONE-HALF TO LILLIAN DORFMAN, BOTH OF BROOKLYN, NEW YORK.

TIE CLASP.

Application filed July 23, 1921. Serial No. 488,187.

To all whom it may concern:

Be it known that we, HERMAN L. DORFMAN and MORRIS GROSSMAN, citizens of the United States, and residents of the city of New York, borough of Manhattan, in the county and State of New York, have invented a new and Improved Tie Clasp, of which the following is a description.

Our invention relates to a tie clasp and 10 aims to provide certain new and useful improvements.

It is well appreciated that any number of different types of tie clasps have been provided, which have engaged the tie and a 15 shirt of the wearer so as to retain the former properly applied with respect to the latter.

All of these devices have been somewhat objectionable in appearance in that even although they were constructed with great 20 care by a jeweler, an article of this nature is more or less unsightly in that the same detracts from the appearance of the wearer.

With this in mind our present invention aims to provide a tie clasp, which will serve 25 to effectually retain the tie properly applied with respect to the shirt, which clasp will, however, be entirely invisible so that the objections heretofore enumerated will be overcome.

30 A further object of our invention is the construction of a device of the character stated which shall be capable of manufacture at a nominal figure and which shall be extremely simple in construction.

35 Further objects of our invention will appear in the annexed specification, taken in connection with the drawings, which latter present one practical embodiment of the invention, and in which

40 Figure 1 is a rear view of a tie and showing a clasp of our improved construction associated therewith;

Figure 2 is a transverse sectional plan view taken along the lines 2—2 of Figure 3;

45 Figure 3 is a sectional side view taken along the lines 3—3 of Figure 2;

Figure 4 is a perspective view of the clasp; and

50 Figures 5 and 6 are side and edge views, respectively, of a slightly different form of clasp.

The essence of our invention consists in

providing a clasp which shall engage the 55 rear face of the forward scarf portion of a tie as well as the second scarf portion thereof and shall retain these parts applied with respect to the shirt, thus rendering the clasp 60 invisible.

A practical embodiment of a clasp of this nature is illustrated in Figures 1 to 4 and it will be seen, referring to the last-named figure, that the same preferably includes a body formed of a single piece of material 65 such as wire, which body presents a pair of U-shaped portions 10, which have their inner arms extending and bent downwardly as at 11 to provide a resilient tongue, the outer arm of one of the U-shaped portions 70 being bent to form a pin 12, the second of the same carrying a guard 13.

Thus, as in Figure 1, the pin 12 may pierce the rear face of the forward scarf 14 of the tie, it being obvious that the device will not 75 be apparent to an observer standing in front of the said tie. Also, the device will not interfere with the tying of the knot 15.

However, when the device is in this position, it will be obvious that as in Figure 2, 80 the rear scarf 16 may be engaged by the tongue 11 of the appliance and lie between the same and the U-shaped portions 10 thereof, and also, this tongue may subsequently 85 be inserted to engage the rear face of the shirt 17 thus retaining the whole in applied position.

Another practical embodiment of our invention is illustrated in Figures 5 and 6 in which a plate 18 is provided, which plate 90 is formed with an integral resilient tongue 19, the plate also being formed with loops 20 capable of engaging and retaining a safety pin 21. This device will operate in the same manner as the device illustrated in Figures 95 1 to 4 in that the body of the plate 18 corresponds with the U-shaped portions 10, the tongue 19 acting as in the same manner as the tongue 11 and the safety pin 21 corresponding with the pin portion 12 and 100 guard 13.

Thus, all the objects set forth in the preamble of the specification are accomplished, and it will be further understood that numerous modifications may be readily resort ed to, without at least departing from the 105 scope of our claims, which are—

1. A tie clasp including a body, a resilient tongue associated with said body, and a pin also associated with said body at a point substantially intermediate the ends of said body said pin extending transversely to the length of said body.
2. A tie clasp including a body bent to provide a pair of U-shaped portions, inner arms of said U-shaped portions being extended to provide a tongue, one of the outer arms of said U-shaped portions being extended to provide a pin, and a guard fixed to the outer arm of the second U-shaped portion, said guard being adapted to cooperate with said pin.
3. A holder of the class described comprising a body portion, a clamping portion integral with the body portion and positioned adjacent thereto, and a safety pin construction integral with said body portion and positioned upon the opposite side of said body portion from the clamping portion. 15
